UNITED STATES PATENT OFFICE.

IRA F. GORDON, OF TRAVERSE CITY, MICHIGAN.

DESIGN FOR A SPRAYER-BODY.

SPECIFICATION forming part of Design No. 30,360, dated March 21, 1899.

Application filed January 16, 1899. Serial No. 702,874. Term of patent 3½ years.

To all whom it may concern:

Be it known that I, IRA F. GORDON, a citizen of the United States, residing at Traverse City, in the county of Grand Traverse and State of Michigan, have invented and produced a new and original Design for a Sprayer-Body, of which the following is a specification.

My invention relates to a new and original design for sprayer-bodies and is illustrated in the accompanying drawings, in which—

Figure 1 is a side elevation, and Fig. 2 a front view.

The leading feature of my design consists in a sprayer-body which is substantially triangular in shape and having curved surfaces, as shown, with a cylindrical barrel having a flattened conical end resting upon said substantially triangular body.

In the said drawings the reference-letter A indicates the body, which is substantially

triangular in cross-sectional form, having the curved surfaces A' and straight ends A².

The reference-letter B indicates the cylindrical barrel, having a flattened conical end B', resting upon the body A.

My design presents a sprayer-body of novel and distinguishing appearance. 25

Having thus described my invention, what I claim as new, and desire to secure by Design Letters Patent, is—

The design for a sprayer-body as herein shown and described. 30

In testimony whereof I have hereunto set my hand in presence of two subscribing witnesses.

IRA F. GORDON.

Witnesses:

EDWARD TAGGART,
CHRISTOPHER HONDELINK.
